Isaac McNary

Setter's Patent

The Schedule referred to in these letters patent and making part of the same containing a description in the words of the said Isaac McNary himself of his improvement in the Franklin Cooking Stove.

To all to whom these Presents shall come:

Be it known that Isaac McNary of the Town of Stafford, County of Tolland and State of Connecticut have invented a new and useful improvement in the Franklin Cooking Stove denominated the Improved Cook Franklin Stove; and that the following is a full and exact description thereof. - In the front part of the Stove is a removable grate & hearth upon which the fuel is placed. Directly back is the oven which opens by a door on each side of the Stove. Upon the top are placed three kettles, one of a larger size, two of a smaller size. The larger kettle is placed near the centre in the forward part of the stove, and the two smaller ones near the back part of the stove. The pipe is placed at the back part of the stove. The fire and smoke passes from the grate below the kettle, and above the oven. This descends behind the oven and goes into the pipe at the side of the stove. There is a tank to which there is affixed a wheel turning a shaft which goes across the stove under the large kettle to which at each end chains are appended which chains are united to the shaft and fastened to the grate. By turning the wheel the wheel and shaft are also turned which winds the chains around the shaft by means of which the grate and hearth upon which the fuel is placed is drawn upward toward at pleasure, communi-
nicating more or less heat to the kettle, and other parts of the stove. What I claim as my ^{own} invention and improvement not previously known in the above described stove is the turning and raising of the grate & hearth at pleasure by means of the above mentioned.

Isaac McNary
